BLENDER JAR

Paul O. Rawson, Jr., Trumbull, Conn., and Frank M. Grunwald, Syracuse, N.Y., assignors to General Electric Company, a corporation of New York

Filed Mar. 27, 1961, Ser. No. 64,507

Term of patent 14 years

(Cl. D89—1)

Fig. 2.

Des. 191,154

PAGE 3

FIG. 3.

Fig. 4.

Fig. 5.

FIG. 1 is a perspective view of a blender jar embodying our design;

FIG. 2 is a front elevation view of the blender jar;

FIG. 3 is a side elevation view of the blender jar;

FIG. 4 is a top plan view of the blender jar; and

FIG. 5 is a cross-sectional view taken on the line 5-5 in FIG. 2.

The dominant features of the design reside in the portions shown in full lines.

We claim:

The ornamental design for a blender jar, substantially as shown and described.
